UNITED STATES PATENT OFFICE.

HENRY ALLENDER, OF DETROIT, MICHIGAN.

HYDROCARBON-GAS MACHINE.

SPECIFICATION forming part of Letters Patent No. 314,412, dated March 24, 1885.

Application filed January 16, 1884. (No model.)

To all whom it may concern:

Be it known that I, HENRY ALLENDER, of Detroit, in the county of Wayne and State of Michigan, have invented new and useful Improvements in Hydrocarbon-Gas Machines; and I hereby declare that the following is a full, clear, and exact description thereof, reference being had to the accompanying drawing, which forms a part of this specification.

10 This invention relates to certain new and useful improvements in gas-machines of that class wherein the gas is produced by bringing gasoline and air into contact, so that the air becomes thoroughly carbureted and is converted into an illuminating-gas.

15 The invention consists in the peculiar construction of the parts, and in their various combinations and operation, as more fully hereinafter described.

20 In the accompanying drawing, which forms a part of this specification, A represents an inclosing-vessel of any suitable size, made, preferably, of galvanized iron. To the bottom of this vessel, and within the same, there is secured one or more cylinders, B, with open tops a. Loosely sleeved upon these cylinders B are other cylinders, C, closed at the top b and open at the bottom.

25 Centrally secured within the cylinders B are guide-posts D, extending from the bottom of the chamber A to the top of such cylinders B. A tube, E, open at its lower end and closed at top, is centrally secured pendent from the top of the cylinder C, and when the latter is in place this tube is sleeved upon the guide-posts D. At the bottom ends these tubes are provided with flanges or tappets c, and similar flanges or tappets, d, are also secured to said tubes E near the top a of the cylinders B.

30 F is a pipe connected at e with a suitable air-pump. (Not shown.) The ends of this pipe F turn upward into the cylinders B through the bottom of the chamber A, and the upper ends of these pipes F terminate at the height 35 of the top a of the cylinder B, where they are provided with the valves G.

35 H are air-outlet pipes connecting at their bottom ends below the bottom of the chamber A with the pipe I, which leads to a small drip-chamber, J, whence another pipe, K, leads to connect with the coil of pipe L. This coil of pipe is made, preferably, in the form shown,

being nearly an elliptical spheroid, so that the spiral descent may be lessened as much as may be necessary to retard the flow of liquid through 55 the same.

M is a rigid arm attached to and projecting from the wall of the cylinder C, and from the outer ends of this arm a rod, N, extends downward, and its lower end is pivotally connected 60 with a bucket, P.

Q is a stop, the purposes of which will be hereinafter explained.

R is a flaring mouth entering the cylinder S, which surrounds the cylinder C, and the top 65 of this cylinder S is provided with an overflow upon a plane lower than the top a of the cylinder B.

The chamber A is filled with gasoline to the height of the dotted lines, as shown, and air 70 being pumped into the pipe F escapes through the valve G into the cylinders B and the cylinder C. Such pressure raises said cylinder C until the flange or tappet c at the lower end of the tube comes in contact with the arm i of 75 the valve and closes it against the admission of more air, when the operation of the pump should cease. By means of the arm M and rod N, as the cylinder C raises the bucket P, which up to this time has rested upon the bottom of the chamber A, and immersed in the gasoline therein, is carried up with said cylinder until the lip h engages with the stop Q, and such engagement tilts the bucket and discharges its contents into the mouth R, and 80 thereby forms a seal like that of a gasometer, wherein water is used for a like purpose. A weight upon the top of the chamber C (after the pump has ceased its operations) gradually forces said cylinder downward, by means of 85 90 which the air therein is forced out through the pipe H, and thence through the pipe I into the drip-chamber J. The gasoline carried up by the bucket P and discharged into the cylinder S will fill said cylinder, thereby not only 95 forming the seal hereinbefore mentioned, but furnishing a sufficient amount of gasoline to pass out through the overflow k, the gasoline thus overflowing passing down the pipe T, which enters the goose-neck trap U of the coil 100 L. Thus we have the gasoline descending slowly through said coil by gravity, and being brought into contact with the air, which is being forced in the opposite direction to the

flow of the gasoline by the pressure upon the cylinders C, and by this means the air is sufficiently carbureted for illuminating purposes, and is carried to the service-pipe through a 5 connection, V, in the upper part of the coil. As the weight forces the air gradually out of the cylinders B and C, the flange or tappet d upon the tube E will strike the arm i of the valve and open the same, so that the operation 10 may be repeated under the action of the air-pump.

The coil L is an important factor in carburetors, as by the peculiar construction of this coil more or less gasoline is allowed to 15 waste. In a vertical coil, where one coil lies upon the top of its fellow, the pitch of the descent is too great for ordinary purposes, giving too great a velocity to the descent of the gasoline and preventing its remaining a sufficient length of time in contact with the ascending air; hence the construction of the coil shown and described herein, where the various convolutions of the coil are so arranged that one will pass inside another, or nearly so, 20 so that the pitch of the descent to the coil may be made far less, and thereby render the flow of gasoline through the same comparatively sluggish, and keeping it longer in contact with the ascending air.

30 Another important feature in this invention is the arrangement by means of which only a small quantity of gasoline is mechanically and regularly supplied through the seal in such a manner that the seal is kept up and the over-flow therefrom furnishes the gasoline for the carbureting purposes in such small quantities that it is all absorbed by the air with which it comes in contact, leaving little or none to pass into the drip.

40 What I claim as my invention is—

1. The combination, in a hydrocarbon-gas machine, of a hydrocarbon and air tank with a carbureting device, an annular seal-chamber, and means, substantially as described, for supplying oil to said seal-chamber, the parts being arranged substantially as specified, whereby the hydrocarbon for the carburetor is supplied from the seal-chamber, as set forth.

2. In a hydrocarbon-gas machine, a carbureting-coil made in the form of an ellipse, each 50 convolution overlapping its fellow, instead of riding upon it, in combination with the trap U, depending from the apex of the coil, and connecting the same at one end with the gasoline-supply, and the air-supply pipe K, connected to the other end of the coil, substantially 55 as and for the purposes set forth.

3. The air-cylinder B, provided with an annular seal-chamber, and the inverted cylinder C, in combination with a carbureting-coil, as 60 I, and an overflow-pipe, as T, the latter constructed and arranged to convey the surplus hydrocarbon from the said seal-chamber to the carbureting-coil, substantially as specified.

4. In a hydrocarbon-gas machine, a telescoping gasometer air-tank made in two parts, with an annular seal-chamber between them, in combination with an air-supply pipe regulated by the movement of one of the parts of the tank, means, substantially as described, for supplying oil to said seal-chamber during each traverse of said moving part, and a carburetor supplied by the overflowing oil from the seal-chamber, as and for the purposes set forth.

5. In a hydrocarbon-gas machine, the combination of a telescoping gasometer air-tank, as B S C, with an air-inlet, F, a valve, G, controlling said inlet, and tappets d c, attached to the moving cylinder, and constructed and arranged to contact with said valve G, and open 80 and close the air-inlet at each traverse of the moving cylinder, substantially as and for the purposes specified.

6. A hydrocarbon-gas machine consisting of the tank A, the gasometer consisting of the 85 cylinders B C S, air-inlet pipe F, valve G, flanges c d on the guide-tube D, overflow-pipe T, air-outlet pipe H I, arm M, rod N, bracket P, deflector Q, carbureting-coil L, and drip-tank J, the parts being constructed, combined, 90 and operating substantially as and for the purposes set forth.

HENRY ALLENDER.
